STERILIZING RECEPTACLE FOR LIGATURE TUBES

Reed B. Harkness and Eleanor E. Lacey, St. Louis, Mo., assignors to The C. Dewitt Lukens Surgical Manufacturing Company, St. Louis, Mo., a corporation of Missouri

Application August 13, 1949, Serial No. 110,202

7 Claims. (Cl. 21—87)

1

This invention relates to sterilizing receptacles for ligature tubes and more particularly to receptacles for containing ligature tubes immersed in a sterilizing solution.

The invention, in general, comprises a receptacle for containing ligature tubes immersed in a sterilizing solution having a label within the receptacle visible from the outside of the receptacle for indicating the type of ligatures contained in the tubes within the receptacle. The label is resistant to the sterilizing solution, both as to the material of which it is composed, and the printing thereon, so that it is unaffected by immersion in the sterilizing solution. The provision of the label within the receptacle, rather than on the outside of the receptacle, has the advantage that the label is protected and remains clearly readable so that there is never any difficulty in determining the type of ligatures contained in the ligature tubes in the receptacle. In a more specific aspect of the invention, the receptacle is provided with a partition or partitions to provide compartments for holding different types of ligatures and label holders are provided on the partition or partitions removably to hold labels so that the type of ligature in a particular compartment may be quickly and accurately determined by viewing the labels from the outside of the receptacle. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated,

Fig. 1 is a view in elevation of a sterilizing receptacle embodying the invention, viewed in the plane of a partition therein, the receptacle being partly broken away and shown in section;

Fig. 2 is a horizontal section taken on line 2—2 of Fig. 1;

Fig. 3 is a vertical section taken on line 3—3 of Fig. 2; and,

Fig. 4 is a vertical section taken on line 4—4 of Fig. 2.

Similar reference characters indicate corres-

ponding parts throughout the several views of the drawing.

Referring to the drawing, there is shown at 1 a receptacle or container consisting of a cylindrical glass jar having a convex bottom 3 and a mouth 5 of reduced diameter. A metal cover 7 fits over the mouth of the jar. The space within the jar is divided into four compartments 9, 11, 13 and 15, open at the top, by a partitioning unit 10 consisting of a pair of partitioning members 17 and 19. The member 17 comprises a generally rectangular sheet metal blank which is bent to have a flat narrow vertical central section 21 and wing walls 23 and 25 diverging from the sides of the central section. As shown, the wing walls are approximately at right angles to one another. At the lower end of the flat central section 21 is an upwardly directed hook 27. This is formed from an integral portion of the sheet metal blank bent upward from the lower end of the flat central section 21 opposite the wing walls. The member 19 comprises a generally rectangular sheet metal blank bent to have a flat narrow vertical central section 31 and wing walls 33 and 35 diverging from the sides of the central section. Like wing walls 23 and 25, the wing walls 33 and 35 are approximately at right angles to one another. At the upper end of the flat central section 31 is a downwardly directed hook 37. This is formed by bending an integral portion of the sheet metal blank downward from the upper end of the flat central section 31 opposite the wing walls 33 and 35.

The partitioning members 17 and 19 are assembled within the jar with the wing walls 23, 25, 33 and 35 forming partitions defining the compartments 9, 11, 13 and 15, by placing the flat central section 31 of member 19 against the flat central section 21 of member 17, with the member 19 higher than the member 17, and sliding the member 19 downward to engage the lower end of section 31 in the hook 27 and the upper end of section 21 in the hook 37. Each wing wall is made of such width that, with the members 17 and 19 assembled as described, the wing walls radiate from the approximate center of the jar substantially to the cylindrical wall of the jar. The height of the wing walls is somewhat less than the height of the jar to the bottom of its reduced-diameter mouth 5. The diameter of the assembly

of members 17 and 19 is greater than the diameter of the mouth 5 of the jar so that the assembly cannot be removed except by disassembling the members 17 and 19 within the jar and tilting them so that member 19 may be removed through the jar mouth. The members 17 and 19 are placed and assembled within the jar by slightly tilting them. Both the bottom and top edges of the wing walls are curved to conform to the convex shape of the bottom 3 of the jar so that members 17 and 19 are reversible. The outer edges of the wing walls extend vertically, closely adjacent the inside of the cylindrical wall of the jar.

At the outer vertical edges of the wing walls 23, 25, 33 and 35, and located at the mid-height thereof, are label holders 43, 45, 53 and 55, respectively. Each label holder is identically formed, consisting of a tongue 57, integral with its respective wing wall, bent to extend laterally at such an angle to the wing wall as to face the cylindrical wall of the jar. The upper and lower margins of the tongue are bent over upon the outer face of the tongue to form upper and lower channels 59 and 61 adapted slidably to receive a label 63. The tongues are curved in plan, i. e., as viewed from above, and extend at such an angle to the planes of their respective wing walls that they resiliently press against the cylindrical wall of the jar when the members 17 and 19 are assembled within the jar. This holds the assembly of members 17 and 19 tightly in the jar and prevents it from rattling. With this arrangement, the label holders also eliminate any possibility of ligature tubes slipping past the outer edges of the wing walls from one compartment to another.

All the label holders 43, 45, 53 and 55 are bent to extend in the same direction from the outer vertical edges of the wing walls when the members 17 and 19 are assembled. As illustrated, the label holder 43 extends from the outer vertical edge of the wing wall 23 toward the wing wall 25 and fronts the compartment 9 defined by these wing walls. The label holder 45 extends from the outer edge of the wing wall 25 away from the wing wall 23 and toward the wing wall 33, and thus fronts the compartment 11 defined by wing walls 25 and 33. The label holder 53 extends from the outer edge of the wing wall 33 toward the wing wall 35 and thus fronts the compartment 13 defined by these wing walls. The label holder 55 extends from the outer edge of the wing wall 35 away from the wing wall 33 and toward the wing wall 23, and thus fronts the compartment 15 defined by wing walls 35 and 23. Thus, each one of the label holders is positioned in the front of its respective compartment so that there is no question as to which compartment the label therein identifies, and the label holders remain in such positions relative to their respective compartments in any rotary position of the assembly 17 and 19 in the jar. The labels 63 consist simply of printed paper labels, which are usually supplied with the ligature tubes, made of a paper which is not adversely affected by the sterilizing solution to be used in the jar, and printed with an ink which is insoluble in the sterilizing solution. Such papers and inks are well known. The labels are inserted in the label holders before members 17 and 19 are placed in the jar by inserting them endwise into the upper and lower channels 59 and 61 of the label holders.

In using the receptacle, appropriate labels are placed in the respective label holders to indicate

the type of ligatures which are contained in the ligature tubes in the various compartments. Supplies of the proper ligature tubes are placed in the proper compartments, and the jar filled with a standard sterilizing solution to cover the tubes. This sterilizes the interior of the jar, the partitioning members 17 and 19 and the outside surfaces of the ligature tubes. The labels are visible through the wall of the jar, and the type of ligatures in the tubes in any compartment may thus be quickly and accurately identified, so that there is no delay in selecting a desired ligature tube.

The invention is particularly useful for the sterile storage of non-boilable ligatures contained in glass ligature tubes. With the invention, supplies of different types of ligatures may be stored in sterile condition in one jar and a desired ligature may be quickly and accurately selected when needed. If the level of the sterilizing solution is lowered by the removal of ligature tubes to such an extent as to expose any tubes, more tubes may be placed in the jar to raise the liquid level, or more sterilizing solution may be added. The provision of a label or labels inside the jar visible from the outside of the jar, whether by having label holders mounted on the partitions, or by providing the labels on the inside of the receptacle in any other way, and whether the receptacle is completely or only partly transparent, is of considerable advantage, as this prevents loss or defacement of the label.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

We claim:

1. A sterilizing receptacle for ligature tubes adapted to hold supplies of ligature tubes immersed in a sterilizing solution comprising a glass jar, partitioning means within the jar dividing the space therein into compartments open at the top, said partitioning means being removable from the jar and having outer vertical edges closely adjacent the inside of the wall of the jar, and label holders, one for each compartment, extending laterally from the outer edges of the partitioning means closely adjacent and in face-to-face relationship with the inside of the wall of the jar in front of the respective compartments, each of said label holders comprising a resilient tongue pressing against the wall of the jar, and formed to hold a label in vertical position closely adjacent the inside of the wall of the jar and facing the outside of the jar.
2. A sterilizing receptacle for ligature tubes adapted to hold supplies of ligature tubes immersed in a sterilizing solution comprising a glass jar, a sheet metal partitioning unit within the jar dividing the space therein into compartments open at the top, said unit being removable from the jar and having outer vertical edges closely adjacent the inside of the wall of the jar, and label holders, one for each compartment, extending laterally from the outer vertical edges of the partitioning unit closely adjacent and in face-to-face relationship with the inside of the wall of the jar in front of the respective compartments and adapted to hold labels facing the outside of the jar, each label

holder comprising a tongue bent to extend laterally at an angle to the respective partition, the upper and lower margins of the tongue being bent over upon the outer face of the tongue to form upper and lower channels adapted slidably to receive a label with the label presented in vertical position closely adjacent the inside of the wall of the jar and facing the outside.

3. A sterilizing receptacle for ligature tubes adapted to hold supplies of ligature tubes immersed in a sterilizing solution comprising a glass jar, a sheet metal partitioning unit within the jar dividing the space therein into compartments open at the top, said unit being removable from the jar and having outer vertical edges closely adjacent the inside of the wall of the jar, and label holders, one for each compartment, extending laterally from the outer vertical edges of the partitioning unit closely adjacent and in face-to-face relationship with the inside of the wall of the jar in front of the respective compartments and adapted to hold labels facing the outside of the jar, each label holder comprising a tongue integral with the respective partition bent to extend laterally at an angle to the respective partition, the upper and lower margins of the tongue being bent over upon the outer face of the tongue to form upper and lower channels adapted slidably to receive a label with the label presented in vertical position closely adjacent the inside of the wall of the jar and facing the outside, the tongues extending at such an angle to the partitions as to resiliently press against the wall of the jar.

4. A sterilizing receptacle for ligature tubes adapted to hold supplies of ligature tubes immersed in a sterilizing solution comprising a cylindrical glass jar having a reduced-diameter mouth, a pair of partitioning members within the jar dividing the space therein into four compartments open at the top, each of said partitioning members comprising a generally rectangular sheet metal blank bent to have a flat vertical central section and wing walls diverging from the central section, the members having their central sections in flatwise engagement and their wing walls radiating outward substantially to the cylindrical wall of the jar, the outer edges of the wing walls extending vertically closely adjacent the inside of the cylindrical wall of the jar under the reduced-diameter jar mouth, and tongues integral with the respective wing walls bent to extend laterally at such angles to the wing walls as to face the cylindrical wall of the jar, each tongue having its upper and lower margins bent over upon the outer face of the tongue to form upper and lower channels adapted slidably to receive a label with the label presented in vertical position closely adjacent the inside of the wall of the jar and facing the outside, all the tongues extending in the same direction from the outer vertical edges of the wing walls.

5. A sterilizing receptacle for ligature tubes adapted to hold supplies of ligature tubes immersed in a sterilizing solution comprising a cylindrical glass jar having a reduced-diameter mouth, a pair of partitioning members within the jar dividing the space therein into four compartments open at the top, each of said partitioning members comprising a generally rectangular sheet metal blank bent to have a flat vertical central section and wing walls diverging from the central section, the members having their central sections in flatwise engagement and their wing walls radiating outward substantially

to the cylindrical wall of the jar, the outer edges of the wing walls extending vertically closely adjacent the inside of the cylindrical wall of the jar under the reduced-diameter jar mouth, and tongues integral with the respective wing walls bent to extend laterally at such angles to the wing walls as to face the cylindrical wall of the jar, each tongue having its upper and lower margins bent over upon the outer face of the tongue to form upper and lower channels adapted slidably to receive a label with the label presented in vertical position closely adjacent the inside of the wall of the jar and facing the outside, all the tongues extending in the same direction from the outer vertical edges of the wing walls, the tongues being curved in plan and bent at such angles as resiliently to press against the cylindrical wall of the jar.

6. A sterilizing receptacle for ligature tubes adapted to hold supplies of ligature tubes immersed in a sterilizing solution comprising a cylindrical glass jar having a reduced-diameter mouth, a pair of partitioning members within the jar dividing the space therein into four compartments open at the top, each of said partitioning members comprising a generally rectangular sheet metal blank bent to have a flat vertical central section and wing walls diverging from the central section, one of said members having a hook at the lower end of its central section receiving the lower end of the central section of the other member, the said other member having a hook at the upper end of its central section receiving the upper end of the central section of said one member, the members having their central sections in flatwise engagement and their wing walls radiating outward substantially to the cylindrical wall of the jar, the outer edges of the wing walls extending vertically closely adjacent the inside of the cylindrical wall of the jar under the reduced-diameter jar mouth, and tongues integral with the respective wing walls bent to extend laterally at such angles to the wing walls as to face the cylindrical wall of the jar, each tongue having its upper and lower margins bent over upon the outer face of the tongue to form upper and lower channels adapted slidably to receive a label with the label presented in vertical position closely adjacent the inside of the wall of the jar and facing the outside, all the tongues extending in the same direction from the outer vertical edges of the wing walls.

7. A sterilizing receptacle for ligature tubes adapted to hold supplies of ligature tubes immersed in a sterilizing solution comprising a cylindrical glass jar having a reduced-diameter mouth, a pair of partitioning members within the jar dividing the space therein into four compartments open at the top, each of said partitioning members comprising a generally rectangular sheet metal blank bent to have a flat vertical central section and wing walls diverging from the central section, one of said members having a hook at the lower end of its central section receiving the lower end of the central section of the other member, the said other member having a hook at the upper end of its central section receiving the upper end of the central section of said one member, the members having their central sections in flatwise engagement and their wing walls radiating outward substantially to the cylindrical wall of the jar, the outer edges of the wing walls extending vertically closely adjacent the inside of the cylindrical wall of the jar under the reduced-diameter jar mouth, and tongues integral with the respective wing walls

bent to extend laterally at such angles to the wing walls as to face the cylindrical wall of the jar, each tongue having its upper and lower margins bent over upon the outer face of the tongue to form upper and lower channels adapted slidably to receive a label with the label presented in vertical position closely adjacent the inside of the wall of the jar and facing the outside, all the tongues extending in the same direction from the outer vertical edges of the wing walls, the tongues being curved in plan and bent at such angles as resiliently to press against the cylindrical wall of the jar.
